UNITED STATES PATENT OFFICE.

VANDIVER J. VAN HORN, OF CHICAGO, ILLINOIS.

GUM-TAPE-HOLDING DEVICE.

1,425,815

Specification of Letters Patent. Patented Aug. 15, 1922.

Application filed April 4, 1919. Serial No. 287,596.

To all whom it may concern:

Be it known that I, VANDIVER J. VAN HORN, a citizen of the United States, residing at Chicago, in the county of Cook and State 5 of Illinois, have invented certain new and useful Improvements in Gum-Tape-Holding Devices, of which the following is a specification.

This invention relates to improvements 10 in devices for holding and moistening paper tape and the like.

The principal object of this invention is the provision of such a device which is adapted to be mounted or supported on a horizontal surface or on a vertical surface, as well as inclined surfaces, provision being made so that the tension means and the moistening means may be adjusted in their proper position regardless of the position of 20 the body of the device as a whole.

A further object of this invention is the provision in a device of this character of the moistening means and the tension and feeding means constructed in a separate, removable and adjustable element, relative to the body of the device.

Another object of this invention is the provision of a plurality of pairs of tension or feeding rolls, certain of which are mounted in a pivotally mounted frame, which frame is provided with the serrated cutting or tearing edge, so arranged that when a strain is applied to the tape in cutting the same, the tension rolls will be forced into engagement with the stationary rolls so as to securely hold the tape against further movement during the tearing or cutting action.

A further object of this invention is the provision, in connection with such a device 40 of a moistening roller, feeding or tension rollers and a cutting edge located short of the moistening roll so that free end of the tape is normally out of contact with the moistening roll and cannot accidentally adhere thereto.

Another object of this invention is the provision of means whereby rolls or reels of different thicknesses may be mounted thereon and whereby one, two or more rolls or 50 reels may be mounted upon the same machine, with the frictional means controlling the feed of the tape from the rolls or reels to the feeding or tension rollers.

Further objects of this invention include

improvements in details of construction and 55 arrangement, whereby a simple and effectively operating mechanism of the character described is provided.

To the accomplishment of the foregoing and such other objects as may hereinafter appear, my invention consists in the construction, combination and arrangement of parts hereinafter described and then sought 60 to be defined in the appended claims, reference being had to the accompanying drawings 65 forming a part hereof, which show, merely for the purpose of illustrative disclosure, a preferred embodiment of my invention, it being expressly understood, however, that various changes may be made in 70 practice within the scope of the claims without digressing from my inventive idea.

In the drawings—

Fig. 1 represents a side elevation of a device constructed to embody my invention and 75 arranged so as to be positioned on or secured to a horizontal surface and having two rolls or reels of paper tape or the like in position for use.

Fig. 2 is a vertical longitudinal cross section of the moistening and feeding and tension rollers taken substantially on line 2—2 of Fig. 6, the tearing position of the tape being indicated in dotted lines.

Fig. 3 is a side elevation of a device constructed according to my invention adjusted 85 so as to be mounted upon or secured to a vertical surface or support.

Fig. 4 is a transverse section taken substantially on line 4—4 of Fig. 3, or a 90 similar line of Fig. 1.

Fig. 5 is a transverse section taken substantially on line 5—5 of Fig. 3, or on a similar line of Fig. 1.

Fig. 6 is a top plan view of the device 95 shown in Fig. 1.

Fig. 7 is a detail vertical transverse section taken substantially on line 7—7 of Fig. 1.

Fig. 8 is a detail side elevation of the front part of the machine, supporting bracket or 100 arm being shown in section to facilitate the disclosure, this view showing the manner of adjustably supporting the unit which includes the moistening means, the tension and feeding means and the cutting means, and is 105 taken looking in the direction of the arrow 8 of Fig. 6.

Fig. 9 is a detail modification.

2

Referring now to the drawings, the numeral 10 designates the body of the device, which is in the form of a thin elongated web member having the securing foot 11 at 5 its rear end and the elongated laterally extending foot member 12 at its front end. To the rear end thereof is connected a vertically extending supporting plate 13 which is provided with the medially located groove 14 to 10 receive the inner nut 15 provided on the inner end of the securing bolt 16, whereby the plate 13 is securely held in vertical position. This plate has the rod or shaft 17 secured thereto and to the body 10 near its 15 lower end projecting laterally or transversely of the device as a whole, and also has the rod or shaft 18 secured thereto at an intermediate point and projecting laterally or transversely of the device, and the inner 20 securing nut being located in the groove or channel 14, as previously described.

Adapted to be positioned on said rods or shafts 17 and 18 are the holding and guiding plate members 19 which are suitably apertured to receive the rods or shafts 17 and 18 and are frictionally held against the reels or rolls of tape by means of the knurled member 20 which is apertured to fit upon the rods or shafts 17 or 18 and has a hub 21 25 provided with a groove 22 and having part of the groove cut deep enough, as at 23, to open into the aperture therethrough. Mounted in this groove and having its end positioned in the deep part 23 thereof is the 30 small end 24 of the conical spring 25, the larger end 26 of which bears against the outside plate member 19, as clearly shown in Fig. 6 of the drawing. Due to this arrangement this knurled member 20 is frictionally held on its rod or shaft and may be moved thereon so as to cause the spring member to force the plate 19 against the reels or webs of tape with a varying resilient pressure so that proper adjustment can be made to prevent the reels or rolls of tape from unwinding 35 too fast and interfering with the proper operation of the mechanism. The lower rod or shaft 17 serves as a guide for the tape or tapes, as clearly illustrated in Figs. 1 and 40 50 3 of the drawings.

The front part of the body of the device is extended upward, as at 27, (see Fig. 1) terminating in a rounded part 28 provided with a plurality of notches 29 and is also 55 centrally provided with the tapered or conical seat 30 to receive the tapered end of the setting or locking screw 31 which passes through a screw threaded aperture 32 provided in the end of the right angled extension 33 of the arm or bracket 34 which projects laterally from the unitary member 35 which forms the support for the moistening, feeding and tension rollers and cutting mechanism, as will now be described.

65 This member 35 comprises the trough part

36, having an intermediate partition 37 which is provided with the recess 38 as is the other side thereof to receive the pintles or stud shaft 39 of the moistening roller 40. This moistening roller is shown as having 70 the longitudinally extending grooves and ribs or corrugations, but the same may be circumferentially arranged, if desired. To the side of the trough 36 and communicating therewith, I provide a cup 41 which is 75 adapted to contain a suitable supply of water or other liquid and in which the finger of the operator may be dipped for moistening part of the tape or any other purposes, as 80 may be desired.

Extending to the rear of the trough member are the supporting members 42 which are connected together at their rear ends by the member 43, Fig. 2, which supporting members are provided with the straight-sided slots 44 to receive the square ends 45 of the shaft 46, which shaft is provided with spacing collars or flanges 47 and rotatably receives the lower tension or feeding rollers 48 which are preferably made of wood having the bore therethrough lined with suitable metallic sleeves 49. These side supporting members 42 are provided with vertically extending arms 50 which are apertured to receive the transversely extending rod or 95 shaft 51 on which the frame 52 for supporting the upper tension or feeding rollers 53 is pivotally supported.

This frame 52 includes the side members 54, one of which is extended to provide the 100 ear 55, which receives the end of spring 56, the other end of which is connected to one of the side members 42, as clearly shown in the drawing. These side members are also each provided on their underside with the 105 straight-sided recess 57 to receive the flattened ends 58 of the transversely extending shaft 59, which is provided with the spacing flange members 60 to properly position the tension rolls 61, which are preferably 110 made of wood having a rubber covering or surface 62 and having their bores lined with suitable metallic sleeves 63. The spring 56 holds these rollers 61 normally against the lower rollers 48, as is well understood.

The front end parts of the side members 54 of frame 52 are connected by means of the member 64, the front end of which is serrated, as at 65, and forms the cutting or tearing edge for the tape. It is to be noted 120 that this edge is removed from the surface of the moistening roller so that when the tape is torn the free end remaining is out of contact with the moistening roller and will not accidentally adhere thereto. It is also to be noted that the rod or shaft 51 125 forms a guiding member for the tape between the tension rollers and the cutting edge 65.

Referring particularly to Fig. 8, it is seen 130

that the laterally extending part of the arm or bracket 34 is cross shaped in cross section, so that one of the horizontally extending webs 66 is adapted to enter one of the notches 5 or recesses 29 in the end part 28 of the body of the device. This construction cooperates with the set screw 31 so as to securely hold the moistening means and tension and feeding means and the cutting means, as a whole, 10 in any adjusted position, and the reason for this, and advantages thereof, are made evident by referring first to Fig. 1 of the drawing and then to Fig. 3.

In the first figure, the device is shown 15 mounted on a horizontal surface or in a horizontal position, whereas in Fig. 3, the device is shown secured to a vertical support or surface, and in both of these positions of the device as a whole, the moistening tension and feeding rollers and cutting mechanism are securely held in their normal horizontal position without regard to the position of the device as a whole. Of course, this is for the purpose of preventing the 20 spilling of any liquid which may be used in connection with the device. It is obvious, that while I have shown the adjustment, merely for a horizontal and vertical position, that the same may be readily adapted 25 for adjustment in various inclined positions merely by the provision of additional notches or recesses 29 in the body member.

It is to be noted that when the device is 30 used in a horizontal position or placed on a desk or other finished article, that it is advisable to use an additional base or support 67, to which the body member 10 is secured. While I have shown this same base 35 or support in connection with the device 40 when mounted in a vertical position, it is to be expressly understood that the same may be omitted and the body member 10 secured by means of its feet directly to the vertical support or surface.

45 A very important feature of this construction resides in the pivoting of the frame 52 in which the upper tension roller 53 is journaled because when the pull or strain is applied to the tape to tear or cut the same on 50 the cutting edge 65 the frame 52 will be turned on the pivot 51 and the rollers 53 caused to clamp the tape tightly against the lower rollers 48 so as to securely hold the tape against feeding forward or backward, 55 whereby the cutting or tearing action is rendered uniform and efficient.

Having described my invention, what I claim is:—

1. A device of the character described, including in combination, a body member having provision for rotatably supporting a reel, a unitary construction mounted on said body member, including a moistening means feeding and tension means and 60 cutting means, said unitary construction be-

ing adjustable relative to said body member so that it may be held in proper position regardless of the position of the body member as a whole.

2. A device of the character described, including, in combination, a body member having provision for rotatably supporting a reel, a unitary construction mounted on said body member, including a moistening means, feeding and tension means, cutting 70 means, an arm extending laterally from said unitary construction and adapted to engage said body member, and securing means passing through said arm and engaging said body member for clamping 80 said unitary construction in adjusted position thereto so that said unitary construction may be held in proper position regardless of the position of the body member as a whole.

3. A device of the character described, including, in combination, a body member having provision for rotatably supporting a reel, a unitary construction mounted on said body member including a trough, a roller, 90 rotatable in said trough, a plurality of oppositely disposed feeding and tension rollers, a frame for supporting the upper feeding and tension rollers, and means for holding said rollers in contact with each other, 95 said frame being provided with a cutting edge.

4. A device of the character described, including, in combination, a body member having provision for rotatably supporting a 100 reel, a unitary construction mounted on said body member including a trough, a roller, rotatable in said trough, a plurality of oppositely disposed feeding and tension rollers, a frame for supporting the upper feeding and tension rollers, and means for holding 105 said rollers in contact with each other, said frame being provided with a cutting edge, said unitary construction being adjustable relative to said body member so that 110 it may be held in proper position regardless of the position of the body member as a whole.

5. A device of the character described, including, in combination, a body member having provision for rotatably supporting a reel, a unitary construction mounted on said body member including a trough, a moistening roller rotatably mounted in said trough, a plurality of feeding and tension rollers, 115 a frame for supporting the upper rollers, said frame being pivotally mounted on said unitary member, and means for holding said upper rollers in contact with said lower rollers, said frame having a cutting edge.

6. A device of the character described, including, in combination, a body member having provision for rotatably supporting a reel, a unitary construction mounted on said body member including a trough, a moisten- 120

ing roller rotatably mounted in said trough, a plurality of feeding and tension rollers, a frame for supporting the upper rollers, said frame being pivotally mounted on said unitary member, and means for holding said upper rollers in contact with said lower rollers, said frame having a cutting edge, said unitary construction being adjustable relative to said body member so that it may be held in a horizontal position regardless of the position of the body member as a whole.

7. A device of the character described, including, in combination, a body member having provision for rotatably supporting a reel, a unitary construction mounted on said body member, including a trough, a moistening roller rotatably mounted in said trough, a plurality of feeding and tension rollers, the lower rollers being mounted to rotate in said unitary construction, a frame for rotatably supporting the upper rollers, said frame being pivotally mounted in said unitary construction, and means for holding said upper rollers in contact with said lower rollers, said frame having its front edge formed as a cutting edge whereby when strain is applied to the tape for cutting the same the frame will be turned on its pivot to force the upper rollers into tighter contact with the lower rollers and tape.

8. A device of the character described, including in combination, a body member having provision for rotatably supporting a reel, a unitary construction mounted on said body member, including a trough, a moistening roller rotatably mounted in said trough, a plurality of feeding and tension rollers, the lower rollers being mounted to rotate in said unitary construction, a frame for rotatably supporting the upper rollers, said frame being pivotally mounted in said unitary construction, and means for holding said upper rollers in contact with said lower rollers, said frame having its front edge formed as a cutting edge whereby when strain is applied to the tape for cutting the same the frame will be turned on its pivot to force the upper rollers into tighter contact with the lower rollers and tape, said cutting edge being removed from said moistening roller so that the free edge of the tape after tearing is not in contact with said moistening roller.

55. 9. A device of the character described, including, in combination, a body member having provision for rotatably supporting a reel, a unitary construction mounted on said body member including a trough, a moistening roller rotatably mounted in said trough, a plurality of feeding and tension rollers, a frame for supporting the upper rollers, said frame being pivotally mounted on said unitary member, means for holding said upper rollers in contact with said

lower rollers, said frame having a cutting edge, said unitary construction having an arm projecting laterally therefrom, said body member having a plurality of notches, said arm having means for engaging any one of said notches, and clamping means cooperating with said arm and the body member to clamp the unitary construction in a selected adjusted position to the body member, so that it may be held in a horizontal position regardless of the position of the body member as a whole.

10. In combination, in a device of the character described, a unitary construction, including a trough having a finger cup part on one side thereof and in communication therewith, a moistening roller rotatably mounted in said trough, a plurality of feeding and tension rollers, the lower rollers being rotatably mounted in said unitary construction, a frame for supporting the upper rollers, said frame being pivotally mounted in said unitary construction, and means for holding said upper rollers in contact with the lower rollers, the frame being provided with a cutting edge.

11. In combination, in a device of the character described, a unitary construction, including a trough having a finger cup part on one side thereof and in communication therewith, a moistening roller rotatably mounted in said trough, a plurality of feeding and tension rollers, the lower rollers being rotatably mounted in said unitary construction, a frame for supporting the upper rollers, said frame being pivotally mounted in said unitary construction, and means for holding said upper rollers in contact with the lower rollers, the front edge of the frame being formed to cut the tape whereby when the tearing strain is applied, the frame will be turned on its pivot to force the upper rollers into more intimate contact with the lower rollers and tape and hold the tape against further feeding movement.

12. A device of the character described, including, in combination, a body member having means for rotatably supporting a reel, a unitary construction including moistening means, feeding and tension means, and cutting means, means for adjustably mounting said unitary construction upon the body member so that the same may be adjusted in a horizontal position regardless of the position of the body member as a whole.

13. A device of the character described, including in combination, a body member having means for rotatably supporting a reel, a unitary construction including moistening means, feeding and tension means, and cutting means, means for adjustably mounting said unitary construction upon the body member so that the same may be

adjusted in a horizontal position regardless of the position of the body member as a whole, said adjustable means including an arm extending from said unitary construction, the body member being provided with a plurality of notches, said arm having means adapted to engage any selected one of said notches, and a screw passing through the end of said arm and engaging 10 said body member so as to clamp said unitary construction to said body member.

14. A device of the character described, including, in combination, a body member having moistening means, feeding and tension and cutting means at one end, and a reel supporting means at the other end, said reel supporting means including a vertically extending plate secured to said body member, and a plurality of shafts secured to said 20 vertically extending plate and projecting laterally therefrom, one of said shafts being adapted to rotatably receive the reel and the other shaft serving as guiding means for the tape or other material of the reel.

15. A device of the character described, including, in combination, a body member having moistening means, feeding and tension and cutting means at one end, and a reel supporting means at the other end, said 30 reel supporting means including a vertically extending plate secured to said body member, a plurality of shafts secured to said vertically extending plate and projecting laterally therefrom, one of said shafts being 35 adapted to rotatably receive the reel and the other shaft serving as guiding means for the tape or other material of the reel, and a frictionally held plate member on said shaft to engage the other side of said reel.

16. A device of the character described, including, in combination, a body member having moistening means, feeding and tension and cutting means at one end, and a reel supporting means at the other end, said 40 reel supporting means including a vertically extending plate secured to said body member, a plurality of shafts secured to said vertically extending plate and projecting laterally therefrom, one of said shafts being 45 adapted to rotatably receive the reel and the other shaft serving as guiding means for the tape or other material of the reel, said shafts being of sufficient length to receive a plurality of reels, and a plurality of vertically 50 extending plate members positioned on said shafts, and means for frictionally holding said plate members and said reels on said 55 shafts.

17. A device of the character described, 60 including, in combination, a body member having moistening means, feeding and tension and cutting means at one end, and a reel supporting means at the other end, said reel supporting means including a vertically 65 extending plate secured to said body mem-

ber, a plurality of shafts secured to said vertically extending plate and projecting laterally therefrom, one of said shafts being adapted to rotatably receive the reel and the other shaft serving as guiding means for the 70 tape or other material of the reel, said shafts being of sufficient length to receive a plurality of reels, and a plurality of vertically extending plate members positioned on said shafts, and means for frictionally holding 75 said plate members and said reels on said shafts, said means including a knurled member having an aperture therethrough and provided with a hub, the hub being grooved, part of the groove being cut deep enough so 80 as to open into the aperture through the knurled member, and a conical spring having its larger end engaging one of said plate members and having its smaller end positioned in said groove and part thereof extending, into the aperture in the knurled member, so as to engage the shaft and frictionally hold the knurled member thereon, movement of the knurled member on the shaft varying the tension of the spring member 85 against the plate.

18. In a device of the character described, including, in combination, a body member having feet whereby the same may be secured in a vertical, horizontal, or other position, reel holding means including an extended plate member secured to said body member, shafts connected to said plate member and extending laterally therefrom, one of said shafts serving as means to rotatively 95 receive one or more reels, the other shaft serving as guiding means for the tape, additional plate members on said shafts and means for frictionally holding the same in position thereon against the reel so as to 100 control the unreeling thereof, a unitary construction on the other end of the body member including moistening means, feeding and tension means and cutting means.

19. In a device of the character described, including, in combination, a body member having feet whereby the same may be secured in a vertical, horizontal, or other position, reel holding means including an extended plate member secured to said body 110 member, shafts connected to said plate member and extending laterally therefrom, one of said shafts serving as means to rotatively receive one or more reels, the other shaft serving as guiding means for the tape, additional plate members on said shafts and means for frictionally holding the same in position thereon against the reel so as to 115 control the unreeling thereof, a unitary construction on the other end of the body member including moistening means, feeding and tension means and cutting means, said 120 unitary construction being adjustable relative to said body member so that the same may always be held in a horizontal position 130

regardless of the position of the body member as a whole.

20. In combination in a device of the character described, the body member, means for rotatably holding a reel thereon, said means including an extended plate member, said plate member being provided with a longitudinal groove, a plurality of shafts secured to

said plate member and having the inner securing nuts positioned in said groove, and additional plate members frictionally held upon said shafts. 10

In testimony whereof I hereunto subscribe my name.

VANDIVER J. VAN HORN.
